Alonzo E. Rhoades.
by *Arthur Browne* Atty.

UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MASSACHUSETTS.

TERRY-LOOM.

1,366,939.

Specification of Letters Patent.

Patented Feb. 1, 1921.

Application filed June 17, 1919. Serial No. 304,859.

To all whom it may concern:

Be it known that I, ALONZO E. RHOADES, of Hopedale, in the county of Worcester and State of Massachusetts, have invented 5 certain new and useful Improvements in Terry-Looms, of which the following is a specification.

The improvements herein described are applicable to terry looms of the character 10 set forth in United States Letters Patent No. 1,322,730 and No. 1,322,731, both dated November 25, 1919. Looms of this character weave toweling with alternating stripes of plain and terry weave. As set forth in 15 the aforesaid patents there are two actuators controlling the beat-up motion, the let-off and the let-back, which together govern the weaving mechanism to produce the desired effects. It sometimes happens in the course 20 of the weaving that the weft breaks, and there may be one or more missing or partial picks before the loom stops. Accordingly, the loom must be turned back so that there 25 may be no missing picks in the weave when the loom is again started. At the same time, it is necessary to prevent the actuation of 30 the let-off roll so that the terry warp will not continue to be fed forwardly, as it will be if the pawl is not thrown out of engagement with the ratchet wheel on the shaft of the terry let-off. Heretofore, it has been necessary to lift by hand the terry actuator 35 controlling the let-off motion to throw the pawl out of engagement with the ratchet wheel on the shaft of the terry-let-off roll, and to hold it in this position while the loom is turned back.

It is the object of the present invention to provide a mechanism whereby the terry 40 actuator will be raised and held in its raised position, thereby disengaging the actuating pawl for the terry let-off roll, so that the loom may be turned back without moving the terry let-off roll, thus giving the weaver 45 both hands free to turn the loom back, and to restart the loom.

The improvements are illustrated in the accompanying drawings, wherein—

Figure 1 is a plan view of so much of the 50 loom as is necessary to show the operation of the present invention. Fig. 2, is a section on the line 2—2 in Fig. 1. Fig. 3 is a section on the line 3—3 in Fig. 1.

As described in the aforesaid patents, the 55 pattern mechanism controls the beat-up mo-

tion, the let-back and the let-off through two actuators, 10 and 11, each shown as a lever pivoted at its outer end. This pattern mechanism need not be here described in detail, being the same as in said patent No. 60 1,322,730. Suffice it to say that a wire 12, leads from the inner end of actuator 10 to the let-back motion, and a wire 13 leads from the inner end of actuator 11 to the beat-up motion, and each forms an operative connection to its controlled mechanisms. A second wire 14 leads from the inner end of the terry actuator 11 to the terry let-off. This wire 14 connects at its lower end with one arm 28 of a bell crank lever, the other 70 arm 29 of which is connected by a link 30 with the spring pressed pawl 20. This pawl 20 is pivotally connected to the upper end of a reciprocating rod 21 which is operatively connected to a cam shaft of the loom to feed 75 the terry warp positively forward during the formation of the terry loops, as described in the aforesaid Patent No. 1,322,730.

The terry warp 15 runs from the usual terry warp beam (not shown) under the 80 idle roll 16, around rough surfaced terry let-off roll 17, over and under idle roll 18, to the harnesses. The ratchet wheel 19, which is acted upon by the spring pressed pawl 20, is fast on the shaft of the let-off 85 roll 17.

In all the respects thus far described the mechanism is identical with that of the aforesaid patents.

When a weft thread breaks, the loom is 90 stopped in the usual manner, but after the thread is broken, there may be one or more missing or partial picks before the loom comes to a standstill. It, therefore, becomes necessary for the weaver to lift the terry 95 actuator 11 by hand so as to disengage the pawl 20 from the ratchet wheel 19, and to maintain it uplifted to render the terry let-off idle while turning the loom back, and restarting the loom. This is a serious inconvenience.

The present invention provides a controller mechanism for the terry let-off actuator, and comprises a hollow shaft A mounted to rock upon a stud B screwed into the pattern 105 mechanism supporting frame C, as shown at D in Fig. 1, and extending beneath the let-back actuator. A nut E, screwing onto the reduced end of the stud B, maintains the shaft A in place. The shaft A carries near 110

its rear end an arm F which is directly beneath the terry actuator 11. Shaft A extends forwardly sufficiently so that its forward end is entirely clear of the actuators.

5 At its forward end in front of the let-back actuator, it carries a handle G.

Normally the controller mechanism is in the idle position shown in dotted lines in Fig. 3, entirely out of the plane of the actuators 10 and 11. When it becomes necessary to lift the actuator 11 and turn the loom back, the weaver has simply to reach for the handle G, which is clear of any other mechanism, and rock the shaft A until the arm F,

15 makes positive engagement with the terry actuator 11 and lifts it. The pawl 20 is thus disengaged from the ratchet wheel 19, thereby rendering it possible to turn the loom backward without turning the let-off roll.

20 Means are employed to maintain the controller in the position in which it maintains the terry actuator in idle position. When the arm F is moved to engage and lift an actuator it is swung upwardly and outwardly beyond its axis until stopped by the fixed stop 68, as shown in Figs. 1 and 3. Accordingly, it is securely held pivoted, and maintains the terry actuator 11 in its raised position. Therefore the weaver can release

25 the handle G and has both hands free to turn the loom back so that when weaving is again started the fabric will be even and there will be no missing picks. When the weaver has turned the loom back it is only necessary for him to turn the handle G and arm F back to idle pendent position, as indicated in dotted lines in Fig. 3, thereby disengaging the terry actuator and permitting it to assume its lower position. Accordingly, less time is consumed by the weaver

30 in correcting the defect, which in turn means

that the loom is out of commission a less time thus doing more work, and the weaver is released sooner to attend to other duties.

In the present embodiment it so happens 45 that the terry actuator must be raised. The terry actuator could just as well be arranged so that it might have to be depressed to disengage the let-off roll, or moved sidewise. The present controller mechanism could be 50 equally well applied to move the actuator in any of these directions.

I claim:

1. A terry loom having a pattern-controlled terry actuator operatively connected 55 to the beat-up motion and to the terry let-off, and a fixed stop in combination with a controller mechanism for the terry actuator comprising a rock shaft mounted upon a fixed stud beneath said terry actuator, said shaft carrying near its rear end an arm directly beneath the terry actuator and carrying near its forward end a handle for rocking said shaft, said arm being normally out of the plane of the terry actuator but 60 adapted to be rocked to cooperate therewith to raise the terry actuator at the will of the operator and to swing past its axis and against said fixed stop so as to hold said actuator in its raised position to permit the loom 65 to be turned back without actuation of the terry let-off.

2. A terry loom having in combination, a 70 terry let-off, a pattern-controlled terry let-off actuator, a fixed stop and a lifter movable to lift said actuator to a position against said stop so as to hold said actuator uplifted, whereby the loom may be turned back without actuation of the terry let-off.

In witness whereof I have hereunto signed 75 my name.

ALONZO E. RHOADES.
